WARM AIR GENERATOR

Filed Aug. 17. 1925

By *Adrian Dyer*

Attorney

UNITED STATES PATENT OFFICE.

CHARLES A. STOLL, OF KANE, PENNSYLVANIA.

WARM-AIR GENERATOR.

Application filed August 17, 1925. Serial No. 50,889.

This invention relates to improvements in warm air generators, as applied to and incorporated in heating apparatus designed for heating of houses and other buildings.

5 One of the objects of the invention is to insure that the maximum amount of heat units expended in inducing heat into the heating medium such as air, will be utilized.

Another object of the invention is to insure 10 that the air to be heated shall attain as high a temperature as possible before being discharged into the area to be heated.

Another object of the invention is to provide means for heating pure atmospheric air, 15 without placing it in contact, or commingling it with the gases and other products of combustion applied in the air heating operation.

The invention has other features which 20 will be more fully described in connection with the accompanying drawings, and which will be pointed out in the accompanying claims.

In the drawings:

25 Fig. 1, is a vertical longitudinal sectional view at line 1—1, of Fig. 2.

Fig. 2, is a sectional view at line 2—2, on Fig. 1.

30 Fig. 3, is a view in cross section at line 3—3, on Fig. 1.

Referring to the drawings, 1, 2, 3, and 4, 35 designate the front, rear, and side walls of the outer casing or container, within which is housed my improved warm air generator.

The casing may be of any suitable material, although I prefer to construct it of sheet iron.

In the bottom wall 5 of the casing, are 40 located a plurality of openings terminating in the air inlet tubes 6, adapted to receive atmospheric air to be heated.

Near the top of the casing and spaced 45 away from said top, is the flue opening 7 which leads by suitable means to the chimney (not shown), for carrying off the products of combustion.

The air inlet tubes 6 are positioned in 50 parallel rows and may be varied in numbers, to suit the size of the generating plant required for a given purpose. The air inlet tubes 6, are all led to a common heat generating retort 8, positioned centrally within the casing. Leading from the heat gen-

erating retort 8, is the hot air conduit 9, which extends from the retort 8 to the top 55 wall of the casing where it discharges the hot air into the area to be heated.

Interposed between the parallel rows of the air inlet tubes 6, is a gas burner 10, comprising a form well known in the art, adapted to generate heat by the burning of gas entering the burner at duct 11, fed from any suitable source of supply.

For the purpose of supplying air to aid in the combustion of the gas emanating from the burner 10, there is provided a plurality 65 of air inlet holes 12 in the bottom of the casing through wall 5.

In the novel arrangement shown, the products of combustion from the gas burner 10, 70 are first applied to the adjacent walls of the air inlet tubes 6, and also to the bottom of the retort 8, and then pass intermediate of the inlet tubes 6, into the main combustion chamber 13, completely surrounding the hot air conduit 9, before escaping through the flue opening 7.

It will be obvious that in the operation of my heat generating apparatus, the atmospheric air is kept free from contamination with the products of combustion.

The positioning of the flue opening through which the products of combustion escape, in the manner shown, at the side and below the top of the combustion chamber, 85 has the effect of retarding the flow of the products of combustion from the combustion chamber, and to retain the same during their heat radiating period, at the upper end of the combustion chamber, thereby effectively utilizing practically all of the heat units contained in the products of combustion.

At the discharge end of the hot air conduit 9, is placed a grille 14 which may be of 95 the usual form well known in the art, equipped with vanes to regulate the discharge of the hot air therefrom.

It will be understood by those skilled in the art, that as the air in the tubes 6, absorbs 100 heat from the heating means, the heated air will flow upward and discharge itself through grille 14, the flow of which will be governed by the degree of heat applied by the heating means, and the temperature, as 105 well as the volume of heated air emanating

from the grille 14, will be governed by the control of gas entering the burner 10, at the duct 11.

While I have shown one form of my invention, I do not limit myself to the specific form shown, as modifications thereof may be made without departing from the spirit of my invention.

What I claim as new, and desire to secure by Letters Patent is:

1. In a warm air generator, the combination of an outer casing having a perforated bottom, a plurality of vertically disposed air flues positioned in parallel rows mounted in apertures in said bottom, a gas burner positioned intermediate of said air flue rows, a horizontally disposed air chamber mounted on the upper ends of said air flues provided with a common communication therewith, a rectangular formed discharge air port located in the upper wall of said air chamber and having a longitudinal dimension comprising several multiples of its dimensional width, an air discharge conduit mounted on said discharge port and formed with a warm air discharge opening in the upper end thereof and having substantially

the same cross sectional form as the discharge port throughout its length.

2. In a warm air generator, the combination of an outer casing having an apertured bottom wall, a plurality of air flues positioned in parallel lines extending upwardly from the apertured bottom wall, a longitudinally disposed air chamber having communication with said air flues, a gas burner interposed between the parallel lines of air flues and adapted to project the products of combustion against the air flues and air chamber in common, a rectangularly formed discharge port located in the upper wall of said air chamber whose longitudinal dimension comprises several multiples of its dimensional width, an air discharge conduit mounted on said discharge port having substantially the same cross sectional form as the discharge port throughout its length and having a discharge orifice positioned out of vertical alinement with said discharge port, for the purposes described.

In testimony whereof I have affixed my signature.

CHARLES A. STOLL.
